(57) **CLAIM**

We claim the ornamental design for a hand-held electroporation device, as shown and described.

DESCRIPTION

FIG. 1 is a top, left, front perspective view of a hand-held electroporation device according to our design, wherein the device is shown having a cap attached thereto;

FIG. 2 is a bottom, right, rear perspective view of the hand-held electroporation device with the cap attached thereto;

FIG. 3 is a front elevation view of the hand-held electroporation device with the cap attached thereto;

FIG. 4 is a rear elevation view of the hand-held electroporation device with the cap attached thereto;

FIG. 5 is a right side elevation view of the hand-held electroporation device with the cap attached thereto;

FIG. 6 is a left side elevation view of the hand-held electroporation device with the cap attached thereto;

FIG. 7 is a top plan view of the hand-held electroporation device with the cap attached thereto;

FIG. 8 is a bottom plan view of the hand-held electroporation device with the cap attached thereto;

FIG. 9 is a top, left, front perspective view of the hand-held electroporation device, shown without the cap attached thereto;

FIG. 10 is a bottom, right, rear perspective view of the hand-held electroporation device;

FIG. 11 is a front elevation view of the hand-held electroporation device;

FIG. 12 is a rear elevation view of the hand-held electroporation device

FIG. 13 is a right side elevation view of the hand-held electroporation device;

FIG. 14 is a left side elevation view of the hand-held electroporation device;

FIG. 15 is a top plan view of the hand-held electroporation device; and,

FIG. 16 is a bottom plan view of the hand-held electroporation device.

The broken lines of the figure drawings are included to show unclaimed subject matter and form no part of the claimed design.
